UNITED STATES PATENT OFFICE.

OTTO LADEMANN, OF BERLIN, GERMANY.

CARVING-MACHINE.

SPECIFICATION forming part of Letters Patent No. 508,951, dated November 21, 1893.

Application filed February 3, 1892. Serial No. 420,173. (No model.) Patented in England December 24, 1891, No. 22,518; in France January 8, 1892, No. 218,545; in Belgium January 8, 1892, No. 97,841; in Italy January 12, 1892, No. 31,107/65, and in Austria-Hungary September 3, 1892, No. 2,395 and No. 14,338.

To all whom it may concern:

Be it known that I, OTTO LADEMANN, of Molkenmarkt 6, Berlin, C, Kingdom of Prussia, and German Empire, have invented a new and useful Carving - Machine, (for which I have obtained Letters Patent in Austria-Hungary, No. 2,395 and No. 14,338, bearing date September 3, 1892; in Great Britain, No. 22,518, bearing date December 24, 1891; in France, No. 218,545, bearing date January 8, 1892; in Belgium, No. 97,841, bearing date January 8, 1892, and in Italy, No. 31,107/65, bearing date January 12, 1892,) of which the following is a specification, reference being had therein to the accompanying drawings.

The object of this invention is a shaping, cutting or reproducing machine which differs from machines such as hitherto constructed in so far that while the latter have their cutting tools carried by suitable supports and their tracer moved against a firmly fixed work block and pattern, the tracer is fixed in machines constructed according to this invention and the tool is arranged to turn upon its own axis only while the pattern, as well as the piece being worked, is fed to the tool by the aid of a table upon which it is fixed.

The great advantage of this machine is that a very rapid rotary motion can be imparted to the cutting tool with a comparatively small expenditure of power and that in consequence of the relative fixity of the cutting tool and of its slight mobility much more accurate work can be produced than heretofore. Furthermore the small mobility of the device carrying the cutting tool allows of the constructions of the machine being simplified while increasing its efficiency and durability so as to reduce the repairs to a minimum.

The new cutting, shaping or reproducing machine is illustrated in the accompanying drawings in which—

Figure 1 is a front view of the same. Fig. 2 is a side view partly in section on line $\alpha\alpha$ of Fig. 1. Fig. 3 is a view of a reproducing machine when the working table is moved laterally. Fig. 4 is a section of the reproducing machine when the work table is moved laterally. Fig. 5 is a front view at an enlarged scale of the pin n connecting the shaft m with

the arm o . Fig. 6 is a side view of Fig. 5. Fig. 7 shows on an enlarged scale the articulated connection of the bearing with the weighted arm o of the machine, and Fig. 8 shows a similar view of said connection, with the bearing, p , lifted and turned up to show the face in elevation.

The tracer b is fixed in the frame a of the machine in such a manner that it cannot be moved laterally. By the side thereof the spindles c are inserted through the frame and are provided with suitable adjusting devices b' in which the working tool rests. Upon the spindles c are keyed the pulleys f .

The carriage k of the machine moves upon the rails j and the axis m is carried by the lateral part of its frame.

The axis m carries the pins n upon which turn the weighted arms o ; these arms being movably connected with the bearings p of the axis q of the table r .

Weights r' suspended to the table r have for their object to maintain the same in such a position that its upper surface may form a horizontal plane.

The arms o are located with weights S in order to establish the equilibrium of the table r . This table r is provided with devices whereby the model and the worked pieces are held in position; these devices are not shown in the drawings. A forward and backward motion can be imparted by means of the wheels j' rolling upon the rails j to the table r which carries the worked pieces t and the pattern t' . The working table r receives a vertical motion from the weighted arms o the axis m turning on its bearings l . The lateral motion of the working table and of the pieces being placed results from the weighted arms o being placed upon the pins n of the axis m and from the movable connection of the bearings p upon the weighted arms o . The table is moved by hand.

The mode of operation of the machine is such that after the spindles c and their tools e are set in rotation the table carries the pieces t to be worked and the pattern t' is fed to the tools the said pieces being then cut correspondingly to the contacts of the tracer with the model or pattern t' .

What I claim, and desire to secure by Letters Patent of the United States, is—

1. In a carving machine, the tracer mounted in a fixed position in the main frame, in combination with a supporting frame or carriage movable horizontally under said tracer, and a working table mounted on said traveling support, by connections which provide for vertical movement thereof, and adapted to receive and hold the pattern and piece to be operated upon, substantially as described.
2. In a carving machine, a tracer fixed in the frame of the machine, in combination with

the horizontally traveling carriage, *k*, the arms, *o*, pivotally supported on the said carriage, the working table, *r*, pivotally supported at one end of said arms, and weights, *S*, mounted on the opposite ends of said arms, substantially as described.

In witness whereof I have hereunto set my hand in presence of two witnesses.

OTTO LADEMANN.
